UNITED STATES PATENT OFFICE.

GEORGE H. REYNOLDS, OF NEW YORK, N. Y., ASSIGNOR OF ONE-HALF TO
CRANE BROTHERS MANUFACTURING COMPANY, OF CHICAGO, ILL.

SAFETY APPLIANCE FOR ELEVATORS.

SPECIFICATION forming part of Letters Patent No. 314,721, dated March 31, 1885.

Application filed December 26, 1884. (No model.)

To all whom it may concern:

Be it known that I, GEORGE H. REYNOLDS, of the city and county of New York, in the State of New York, have invented a new and useful Improvement in Safety Appliances for Elevators, of which the following is a specification.

My invention relates to that class of safety appliances for elevator-cars comprising an air-resistance plate or board, or a "parachute-plate," as it may be termed, which is arranged below the car, and constitutes a stop to prevent the operation of the safety pawls or dogs. When the car acquires an undue speed in descending, the resistance of the air in the well will buoy up or lift said plate and release the safety pawls or dogs. This plate or board has been hung or pivoted as a lever below the car, and the longer or heavier arm of the lever 15 has formed or carried the stop to hold the safety pawls or dogs out of operation; but heretofore this plate or board has not been so connected that the safety pawls or dogs would be released instantly in case the hoisting-cables broke, but has only acted when the car had 20 acquired such a speed in falling as would cause the plate or board to move by resistance of the air.

One object of my invention is to so hang 30 the plate or board that an obstruction in the well at any point in the area of the bottom of the car, whether on one side or the other of the fulcrums or trunnions of the plate or board, will raise the latter and release the safety pawls or dogs; and another object is to so connect the plate or board with the hoisting-connection that it will be raised instantly on the breaking of the hoisting-cables and release the safety pawls or dogs before the car can 35 require any acceleration of speed in falling. The first object I accomplish by providing on the car hangers or brackets for the fulcrums or trunnions of the plate or board, which are slotted or open, so that the plate or board will 40 be raised by any obstruction below the car, whether on one or other side of the fulcrums or trunnions; and the second object I accomplish by connecting the plate or board with the hoisting-connections or safety-spring, so 45 that when the cables break the safety-spring 50

will by its action instantly raise the plate or board and release the safety pawls or dogs.

In the accompanying drawings, Figure 1 is a vertical section of the lower portion of a car with safety appliances embodying my invention. Fig. 2 is a horizontal section of the safety appliances and guides on the plane of the dotted line x x , Fig. 1. Fig. 3 is a vertical section on the plane of the dotted line y y , Fig. 1; and Fig. 4 is a side view of a car and 55 appliances for throwing in the safety dogs or pawls in case of the hoisting-cables parting.

Similar letters of reference designate corresponding parts in all the figures.

I will refer first to Figs. 1, 2, and 3. A designates the car, which may be of any suitable construction, and in itself forms no part of my invention.

B designates the upright guides at opposite sides of the elevator-shaft, and a designates 60 slides on the bottom of the car, which fit these guides. The car is also provided with bearings a' , here shown as made in the same castings with the slides a , having journaled in them a shaft, b , at opposite ends of which 65 are fixed safety dogs or pawls c , which traverse along wood safety-strips d on the guides B as the car rises and falls. These strips d 70 may be multiple strips—that is to say, they 75 may be each composed of two or more sections glued together, and the dogs or pawls c 80 may engage with the edges of the sections. This construction of safety-strip is shown and 85 described in my allowed application for United States Letters Patent, Serial No. 143,524, and filed September 20, 1884, and its advantages 90 are that it prevents the strip from warping, and also tends to prevent the splitting of the wood strip in advance of the dog or pawl. In 95 my said application the lower dogs or pawls no the car are connected by rods with corresponding upper dogs or pawls, and I have here shown the shaft b as having arms b' , which are connected by rods b^2 with upper dogs. (Not here shown.) Below the car is 100 suspended what I term an "air-resistance plate or board," C. As here shown, it consists of a frame, e , composed of wood or metal, and having nearer one edge than the other projecting fulcrums or trunnions e' . By these ful-

erums or trunnions it is hung or pivoted in slotted or open hangers or bearings *f*, depending from the car *A*. This device *C*, therefore, forms a lever, the long arm of which slightly preponderates in weight and rests lightly on hangers or supports *g*, depending from the car *A*. As shown, that bar of the frame *e* which is parallel with and nearest the fulcrums *e'* is heavier than the other parts of the frame, and this greater weight serves to more or less counterbalance the longer arm of the lever or frame; but I may also provide a weight, *h*, adjustable along a bar, *h'*, on the under side of the frame, and this may be set so as to balance the frame as nearly as is desired. The portion of the frame *e* which constitutes the longer arm of the lever is covered with sheet-iron *e''*, or other material which is indestructible by elements or by vermin, and offers a surface on which the air may act to lift the plate *C* as the car descends. On the shaft *b* is an upwardly-projecting arm, *b'*, and on the frame *e* is a shoulder or catch, *i*, which bears against the arm *b'*, and by preventing it from swinging outward holds the dogs or pawls *c* out of action. If the plate *C* be raised to take the catch or shoulder *i* out of the way of the arm *b'*, the weight of the arms *b'* and rods *b''*, aided by the power of a spring, if found necessary, will cause the shaft *b* to turn in a direction to throw the dogs or pawls into the safety-strips *d*. The plate *C* is to be weighted and balanced as desired, so that when the car is moving at the normal speed the plate *C* will remain at rest on the hangers *g*, as shown. Now, if the speed increases by any reason beyond the predetermined limit, the resistance of the air will lift the end of the plate *C*, which rests on the hangers *g*, because the covering thereof offers a surface for the air to act on, and will raise the shoulder or catch *i* and release the arm *b'*. Not only will this plate *C* be raised by the resistance of air, but if there be any obstruction in the elevator-shaft the plate will be raised on striking it enough to release the arm *b'*, the open or slotted hangers permitting the plate to lift at any point, whether the obstruction be on one or other side of the fulcrums or trunnions *e'*. To offer a guard which will meet any obstruction and cause the lifting of the plate *C*, I may cover all that part not covered by sheet

metal *e''* with wire-gauze, as shown at *e'''*, which will strike any obstruction, but will be little affected by the resistance of air.

55

In Fig. 4 I have represented a car *A* in its hoisting-cage *A''*, and connections whereby the plate or board *C*, which may be suspended or hung in any of the ways before described, may be lifted to release the safety pawls or dogs *c* when the hoisting-cables *j* break. These cables are attached to a shackle or hoisting-connection, *k*, and when the cables are intact this shackle or connection is lifted or held in the position shown, and thereby holds a spring, 60 *l*, compressed or in a state of tension.

m designates a cord or other flexible connection attached at one end to the spring *l*, and passing thence over pulleys *m'* down to the plate *C*, to which it is attached. When the cables *j* break, the expansion of the spring *l* lifts the plate or board *C*, and releases the safety devices before the car can acquire any momentum.

What I claim as my invention, and desire 75 to secure by Letters Patent, is—

1. The combination, with an elevator-car and safety devices therefor, of an air-resistance plate or board provided with trunnions, hangers, or brackets on the underside of the car, 80 constituting open or slotted bearings, which support the trunnions and permit of their rising, and a catch upon said plate or board for holding the safety devices, out of operation, whereby the said plate or board will be raised 85 to release the safety devices in case of its striking any obstruction at any part of its surface, substantially as herein described.

2. The combination, with an elevator-car and its safety dogs or pawls, of a safety-spring 90 which is held compressed when the hoisting-cables are intact, a plate or board arranged below the car, to be lifted by the resistance of air when the desired speed is exceeded, and forming a stop or catch for the safety dogs or 95 pawls, and connections whereby said plate or board will be raised by the safety-spring in case of the cables parting, substantially as herein described.

GEO. H. REYNOLDS.
